UNITED STATES PATENT OFFICE.

EDUARD FRIEDRICH, OF LEIPZIG-PLAGWITZ, GERMANY.

CRUSHER.

1,078,342.

Specification of Letters Patent.

Patented Nov. 11, 1913.

Application filed May 8, 1912. Serial No. 695,922.

To all whom it may concern:

Be it known that I, EDUARD FRIEDRICH, engineer, a citizen of the Empire of Germany, residing at Leipzig-Plagwitz, Germany, residing at Leipzig-Plagwitz, Germany, 5 many, have invented certain new and useful Improvements in Crushers, of which the following is a full, clear, and exact description.

My invention relates to improvements in crushers, and more particularly to that class 10 of crushers in which two stationary jaws each coöperating with a reciprocating movable jaw are disposed one above the other, so that the upper pair of jaws has the function of breaking up the material to be crushed 15 into pieces of a certain size, while the lower pair of jaws has the function of reducing the material supplied thereto from the upper pair to the desired degree of fineness.

The object of the improvements is to provide 20 a crusher of this class in which a comparatively small number of bearings is required, and in which the relative distances of the jaws of each pair at the lower ends thereof can conveniently be adjusted independently 25 of each other, so that the lower movable jaw can be set according to the desired degree of fineness of the material and without interfering with the crushing effect of the upper pair of jaws.

With this and other objects in view my invention consists in providing an operative connection between the upper end of the lower movable jaw and the lower end of the upper movable jaw, or with an arm having 35 a rocking movement on the driving eccentric or cam, and providing a rear abutment for the lower movable jaw at the lower end thereof, the novel features of my invention being particularly defined in the appended 40 claims.

For the purpose of explaining the invention several examples embodying the same have been shown in the accompanying drawings, in which the same letters of reference 45 have been used in all the views to indicate corresponding parts.

In said drawings—Figure 1, is a vertical section of the crusher taken on the line A—B of Fig. 2, Fig. 2, is a plan of the 50 crusher shown in Fig. 1, Fig. 3, is a partial vertical section illustrating a modification of the crusher shown in Figs. 1 and 2, and Fig. 4, is a vertical section of a further modification of the crusher.

Referring to the example illustrated in Figs. 1 and 2 of the drawings, the frame of

the crusher consists of an upper section 1 and a lower section 2 secured to or made integral with each other. The upper section 1 is formed by longitudinal walls 3 and 4 and transverse walls 5 and 6, while the lower section consists of transverse walls 5' and 7 and longitudinal walls of which only the wall 3' is shown. The lower frame section is narrower than the upper one. 60

The longitudinal walls 3 and 4 of the upper section are provided with bearings for a transverse driving shaft 8 which at opposite ends carries fly wheels 11 and 12, and at one end loose and fast pulleys 9 and 10 respectively. The part of the shaft intermediate the walls 3 and 4 is in the form of an eccentric 13 on which an eccentric strap 14 having an arm 15 is mounted. By the rotation of the shaft 8 reciprocating movement 70 is imparted to the arm 15. Laterally of the support or fulcrum 8 a shaft 27 is mounted on the longitudinal walls 3 and 4 on which support is mounted to rock a movable crusher jaw 26, which coöperates with a preferably vertical stationary jaw 31 secured to the transverse wall 5. Reciprocating movement is imparted to the jaw 26 from the eccentric arm 15 by means of a toggle mechanism. The latter consists of pressure 80 plates 19 and 20 fitting with one of their edges in rounded grooves 16 and 17 at the lower end of the arm 15 and with their opposite edges respectively in a similar groove 25 of the movable jaw 26 and a groove 21 90 formed in the front face of an adjustable wedge block 22. The latter is guided between lugs 22', 22' secured to or made integral with the longitudinal walls 3 and 4, and it is adjusted toward and away from the arm 15 by means of a wedge block 23 95 engaging the wedge block 22 at its rear and adapted to be shifted vertically by means of one or more adjusting screw bolts 24 passing through one or more lugs 24'. Below the 100 groove 25 the movable crusher jaw 26 is equipped with a hook 28 which is engaged by a rod 29 acted upon by a spring 30, the rod 29 and spring 30 having the tendency to retract the movable jaw away from the 105 stationary jaw 31.

At its lower end the movable jaw 26 is formed with a pair of eyes 32 within which a pin 33 is mounted. On the latter is pivotally mounted the upper end of the lower 110 movable jaw 34, which at its lower end is formed with a series of rounded grooves 35.

Any one of the said grooves is engaged by one edge of a pressure plate 36 which with its opposite edge engages one of a series of similar grooves 37 formed in an abutment plate 38. The latter is horizontally guided between upper and lower lugs 38', and it is adapted to be adjusted toward and away from the movable jaw by means of a wedge block 39 engaged by an adjusting screw bolt 40.

The lower movable jaw 34 co-operates with a stationary jaw 41 secured to the transverse wall 5'. As shown the said stationary jaw is disposed in inclined position so as to approach with its lower end the transverse wall 5', and the lower movable jaw is inclined at an angle to the vertical which is larger than the angle of inclination of the upper movable jaw 26. The stationary jaw 41 thus has an "overhanging" surface, which greatly facilitates the falling off of any crushed material that may stick to said stationary jaw. Below the series of grooves 35 a hook 42 is secured to the lower movable jaw 34, and this hook is engaged by a rod 43 acted upon by a spring 44, which rod and spring tend to retract the movable jaw away from the stationary jaw 41.

The operation of the crusher shown in Figs. 1 and 2 is as follows: Rotation of the shaft 8 imparts movement to the upper movable jaw 26 by the toggle mechanism consisting of the arm 15 and the pressure plates 20 and 19, so that the said movable jaw is rocked on the fulcrum 27 toward and away from the stationary jaw 26, and the lower movable jaw 34 takes part with its upper end in such reciprocating movement since it is connected with its upper end to the upper movable jaw 26 by the pin 33. The left-hand edge of the plate 36 forms a fulcrum for the movable lower jaw 34. Thereby the material to be crushed, such as ore, is reduced between the upper jaws in a preliminary way, whereupon it falls between the lower jaws 34 and 41, where it is reduced to the desired degree of fineness. As the lower jaws 34, 41 are inclined at a larger angle than the upper jaws 26, 31, the material remains between the lower jaws a sufficient length of time to be uniformly reduced to the desired degree of fineness.

By adjusting the screw bolts 24 the discharge opening from the upper crusher jaws can be adjusted, whereby the crushing effect of the upper jaws is regulated. In a similar way the discharge opening from the lower jaws can be adjusted by means of the lower screw bolts 40. Thereby the degree of fineness of the material finally discharged from the crusher can be regulated, so that a material is obtained which is either in the form of powder, or of fine or coarse granules. It will readily be understood, that the upper and lower jaws are adjusted inde-

pendently of each other, so that for instance when regulating the degree of fineness of the lower jaws the crushing effect of the upper jaws is not altered. This independent adjustment of both jaws is furthermore important in cases where the upper and lower jaws are not uniformly worn.

By placing the lower pressure plate 36 in either one of the grooves 35 and 37 disposed one above the other the crushing stroke of the lower end of the lower movable jaw can be adjusted independently of the stroke at the lower end of the upper movable jaw 26, as may be required for example in view of the character of the material to be crushed.

In the position of the parts shown in Fig. 1 in which the pressure plate 36 engages the lowermost grooves 35 and 37 the stroke of the lower end of the movable jaw 34 is almost zero. By placing the said pressure plate within one of the upper grooves 35, 37 the stroke at the lower end of the lower movable jaw is increased, because the leverage below the pressure plate 36 providing a fulcrum for the movable jaw is thereby increased, while the leverage above the said fulcrum is reduced. As shown in Fig. 1 the series of grooves 35 and 37 are disposed parallel to each other, so that the same pressure plate 36 can be used in any of the grooves. If desired the said series of grooves may be arranged at an angle to each other as has been illustrated in Fig. 3, in which the grooves 37^a provided in the abutment block 38^a are disposed in a vertical plane. If in this case it is desired to change the crushing stroke at the lower end of the lower movable jaw 34, pressure plates 36^a, 36^b, or 36^c of different lengths are placed into the corresponding grooves 35, 37^a, as has been indicated in Fig. 3 in dotted lines.

The driving mechanism of the upper movable jaw may be modified in various ways. For example, the rocking movement may be imparted to the said jaw by a shaft taking the place of the support 27 and equipped with a cam disk connected with the upper jaw. In this case the upper movable jaw may at the same time be acted upon by the eccentric 13, eccentric strap 14, and arm 15 provided on the shaft 8 and the pressure plates 19 and 20 co-operating therewith, or the said shaft, the eccentric, and one of the pressure plates may entirely be omitted, in which case the jaw 26 is fulcrumed by means of a single pressure plate on a stationary block which corresponds to the block 22 as shown in Fig. 1.

In Fig. 4 I have shown an example in which the lower movable jaw is directly connected to the eccentric-arm 15 by means of a pivot pin 33' or the like. This construction operates on the same principle as those described above. The pivot pin 33' connects

the lower jaw 34 with an extension 45 of the arm 15. In this case also the upper movable jaw 26 may if desired be mounted with its upper end on a driving cam.

5 Apart from the parts specifically referred to the example shown in Fig. 4 is similar to that shown in Figs. 1 and 2, and corresponding parts have received the same numerals of reference, so that a detailed description 10 may be dispensed with.

10 I claim herein as my invention:

1. In a crusher, the combination with a pair of upper jaws and a pair of lower jaws adapted to receive the material being crushed from the upper pair, of a fulcrum for one of the jaws of the upper pair located at the upper end thereof, a fulcrum for one of the jaws of the lower pair located at the lower end thereof, and means, 15 common to said fulcrumed upper and lower jaws, acting on the lower end of the upper jaw and the upper end of the lower jaw to impart rocking movement thereto.

2. In a crusher, the combination with upper stationary and movable jaws, and lower stationary and movable jaws adapted to receive the material being crushed from the upper jaws, of common means acting on the lower end of the upper jaw and on the upper end of the lower jaw to reciprocate said upper and lower movable jaws toward and away from the stationary jaws coöperating therewith, and means to adjust said movable jaws relatively to the stationary jaws coöperating therewith.

3. In a crusher, the combination with upper stationary and movable jaws, and lower stationary and movable jaws adapted to receive the material from the upper jaws, of a fulcrum for the upper end of the upper movable jaw, a fulcrum plate pivoted to a stationary part of the crusher and having a pivotal connection with the lower end of the lower movable jaw, and common operating means connected with the upper end of the lower movable jaw and with the lower end of the upper movable jaw, to impart motion to said jaws.

4. In a crusher the combination with a pair of upper jaws, and means to impart reciprocating movement to said jaws relatively to each other, of a pair of lower jaws both inclined from the vertical toward the same side thereof and adapted to receive material being crushed from the upper jaws, and means to impart crushing movement to said lower jaws relatively to each other.

5. In a crusher, the combination with upper and lower stationary jaws, of an upper 60 movable jaw fulcrumed at its upper end and coöperating with said upper stationary jaw, a lower movable jaw fulcrumed at its lower end and coöperating with said lower stationary jaw, a pivotal connection between the upper end of the lower movable jaw and

the lower end of the upper movable jaw, and means for actuating said movable jaws.

6. In a crusher, the combination with an upper movable jaw fulcrumed at its upper end, and a lower movable jaw fulcrumed at its lower end, of a pivotal connection between the upper end of said lower jaw and the lower end of said upper jaw, additional upper and lower jaws facing the above-mentioned jaws and coöperating therewith, and means for effecting a relative movement of the coöperating jaws.

7. In a crusher, the combination with an upper movable jaw fulcrumed at its upper end, and a lower movable jaw fulcrumed at its lower end, of a reciprocating actuating member having a pivotal connection with the upper end of said lower jaw, and an operative connection with the lower end of said upper jaw, and additional upper and lower jaws facing the above-mentioned jaws and coöperating therewith.

8. In a crusher, the combination with converging upper jaws arranged to perform a preliminary crushing operation, of converging lower jaws adapted to receive the material from the upper jaws and to crush it further, the lower jaw which has an upwardly-facing working surface, forming a greater angle with the vertical than the upper jaw which has an upwardly-facing working surface, and means for effecting a relative movement of the coöperating jaws to crush the material between them.

9. In a crusher, the combination with upper stationary and movable jaws, and lower stationary and movable jaws, adapted to receive the material from said upper jaws, of a fulcrum for one of the upper jaws, located at the upper end thereof, a fulcrum for one of the lower jaws located at the lower end thereof, and means, common to said fulcrumed upper and lower jaws, and acting directly on the lower end of said upper jaw and also acting directly on the upper end of said lower jaw, to impart a rocking movement to both movable jaws.

10. In a crusher, the combination with a pair of upper jaws and a pair of lower jaws adapted to receive the material from the upper pair, a fulcrum for one of the jaws of the upper pair located at the upper end thereof, a fulcrum for one of the jaws of the lower pair, located at the lower end thereof, and means, common to said fulcrumed upper and lower jaws, and connected directly with the lower end of the upper jaw and also connected directly with the upper end of the lower jaw, to impart a rocking movement to said fulcrumed jaws.

11. In a crusher, the combination with a pair of upper jaws and a pair of lower jaws adapted to receive the material from the upper pair, a fulcrum for the upper end of one of the upper jaws, a fulcrum for the

lower end of one of the lower jaws, a pivotal connection between the upper end of said fulcrumed lower jaw and the lower end of said fulcrumed upper jaw, and means, attached to said pivotal connection, for actuating said connected fulcrumed jaws.

12. In a crusher, the combination of a stationary upper jaw and a stationary lower jaw disposed at an angle to the said upper jaw, movable upper and lower jaws co-

operating with said stationary jaws, and means for operating the movable jaws.

In testimony whereof I have signed this specification in the presence of two subscribing witnesses.

EDUARD FRIEDRICH.
